UNITED STATES PATENT OFFICE.

SØREN DAVIDSEN, OF TONSBERG, NORWAY.

REGULATING DEVICE FOR ELECTRODE BOILERS.

Application filed January 21, 1928, Serial No. 248,414, and in Norway February 5, 1927.

My present invention relates to boilers provided with electrodes for heating the water by means of electric energy. Several constructions of such boilers are already known, 5 wherein the water is utilized as a resistance connecting the electrodes inside the boiler so as to receive heat from the electric current flowing from one electrode through a regulated path of water to another electrode. The 10 regulation of the boiler is effected by varying the length of water path or paths for the current in dependency of the temperature or pressure within the boiler, said paths being shortened in case the temperature or pressure 15 decreasing beyond a certain minimum and being prolonged in case the temperature or pressure increasing beyond a certain maximum. Such regulation of the length of the water paths for the current is effected by adjusting the mutual position of the electrodes. 20 The mechanism effecting such adjustment should be of such a nature that a small regulating impulse received from devices under the influence of the boiler temperature or 25 pressure is transferred into a comparatively long travel of the member effecting the adjustment of the electrodes proper.

One of the objects of the present invention is to provide a simple and effective transferring device to be inserted between the impulse member and the adjustment member, and which transferring device fulfills the requirements stated above.

Another object of the present invention is 35 to provide a simple and effective impulse device, i. e. one being under the influence of the boiler conditions and actuating the said impulse member, so as to transmit thereto a comparatively long impulse travel even at 40 relatively small variations in the conditions (temperature and/or pressure) inside the boiler.

I shall now proceed to describe my invention by way of an illustrating embodiment 45 with reference to the accompanying drawing, but it should be understood that the invention is not restricted to the constructions shown therein or described hereinafter.

Figure 1 is a plan view of a boiler, partly 50 in section, showing particularly the said transferring device.

Figure 2 shows in elevation a part of a boiler partly in vertical section.

Figure 3 is another elevation of parts of 55 the boiler showing partly in section the es-

sential members taking part of the entire regulation.

Figure 4 shows diagrammatically a modified form of the transferring mechanism.

Figure 5 shows another modification. 60

Inside the ordinary cylindric boiler shell the electrodes 1 and counter-electrodes 2 are arranged. The electrodes 2 are fixedly mounted on bolts 3 attached to the top cover 4 of the boiler and insulated therefrom. Preferably I use three sets of electrodes 1 65 angularly displaced at 120° so as to be located symmetrically around the vertical axial line of the boiler (see Figure 1). Each set of electrodes 1 consists of spaced parts directed inwardly (Figure 2), and between them project similar spaced parts of electrode sets 2 which are mounted on a common central bar 5 or spindle mounted rotatably in the top cover 4 and bottom cross 6. The electrodes 1 embrace each an angular space of 60° and so do the electrodes 2. Consequently, the latter 2 may be turned in between 1 as shown in the drawing, whereby the water paths for the current from the parts 1 to the 70 parts 2 will be a minimum, consequently the electric energy consumed by the boiler a maximum. Or the electrodes 2 may be rotated through 60° to the position shown in dash-and-dot lines in Figure 1, wherein the said 75 paths will be maximum and the consumed energy a minimum. Between these extreme positions the electrodes 2 may be automatically regulated so as to cause at any time the pressure or temperature within the boiler to 80 remain between certain limits. 85

The adjusting member for the electrodes 2 is shown as an arm 7 attached to the spindle, and the impulse member is shown as a piston rod 8 receiving its motion from a device described more detailed hereinafter. 95

The transferring device is inserted between the arm 7 and the rod 8 and consists of three links *a*, *b*, *c*. All these links are at one end pivotally connected together as at 9, but their other ends are differently arranged. The other end of link *b* is pivoted as at 10 to the fixed cross 6, that of link *c* is pivoted as at 11 to the outer end of arm 7, and that of link *a* is pivoted as at 12 to the inner end of the 100 rod 8.

If now rod 8 is moved a short distance inwardly, so that its inner pivot 12 takes the position 12' (Figure 1), the common pivot end 9 of link *b* must swing about the fixed 110

pivot 10 to the position 10', thereby taking along with it the interconnected ends of links *a* and *c*. Consequently the inner end of link *c* makes a long travel which is transferred 5 to arm 7 the outer pivot 11 of which will thereby take the position 11', wherein this arm 7 has turned the movable set of electrodes 2 through 60°.

In some cases, particularly in large or high 10 boilers, it may be desirable to cause electrodes 2 arranged in a lower part of the boiler, where the water is not so hot, to perform a smaller angular regulating movement than electrodes arranged in the upper part of the boiler. In 15 such case the electrodes 2 may be arranged in groups each group being adjusted by an arm $\frac{7}{2}$, $\frac{7}{3}$ etc. (Figure 4) of different lengths each arm being connected by a separate link *e*, *e*₂, etc., to the common pivot *c*. As will be seen 20 from Figure 4 the end point 11² of arm $\frac{7}{2}$ is swung only to point 11³ through a smaller angle than the point 11 of arm 7, hence the two groups of electrodes are adjusted through different angles.

25 Similar other modifications are included in my invention.

Different groups of electrodes 2 may also be mounted on differently located vertical axes, and in such cases the transferring mechanism will take a corresponding form.

The impulse mechanism effecting the travel 30 of the rod 8 comprises a closed container arranged inside the boiler and forming part of a closed system filled with a liquid. The 35 container may be a coil 13 arranged at a suitable level in the boiler and filled for instance with oil. This coil 13 at the upper end is connected by a pipe 14 to a vertical pipe 15 arranged outside the boiler and conducting down to the rear part of a piston cylinder 16 40 provided with a piston 17 for the rod 8 and being also suitably connected with a flexible diaphragm 18. The rod is pulled outwards by a helical spring 19.

45 If the boiler is intended to heat water to a temperature below 100° C., the coil 13 regulates according to the temperature. According as the latter rises, the oil in coil 13 will be heated and be extended to a larger volume, 50 whereby it is forced partly out into the pipes 14, 15 and cylinder 16 likewise filled with oil. Consequently the piston 17 is pressed inwards together with rod 8 so as to swing electrodes 2 into a position for a lower consumption of 55 electric energy. When again the temperature within the boiler sinks, the pressure of oil upon piston 17 is correspondingly relieved, so as to enable spring 19 to retract rod 8 and adjust the electrodes 2 for a higher consumption 60 of energy.

In case the boiler is used to develop steam at some desired pressure, the temperature and/or pressure prevailing within the boiler may cause the automatic adjustment of the 65 electrodes. Figure 5 shows a modification,

wherein the lower end of coil 13 is provided with a flexible end wall constructed as a bellow-like member 20. At a rising pressure within the boiler the walls of bellow 20 will be pressed towards each other, whereby a 70 quantity of oil is forced out into the coil 13 thereby increasing the pressure in cylinder 16 and forcing piston 17 and rod 8 inwards. Consequently the mechanism regulates in dependency of the temperature and pressure 75 conditions combined.

The coil 13 and pipes 14, 15 may also be dispensed with. In this case the rod 8 and cylinder 16 is arranged at the right hand side (Figure 3) of point 12 and the spring 19 is 80 made as a compression spring tending to force piston 17 with rod 8 inwards, consequently as before to the left in Figure 3, whereas the diaphragm 18 is pressed outwards by the boiler pressure so as to tend to 85 carry rod 8 outwards (to the right). It will be understood that the container 13 is thereby replaced by the inside portion of cylinder 16 between piston 17 and diaphragm 18, the latter forming a flexible wall instead of the 90 bellow 20.

The system filled with liquid is connected at a suitable place to a device for supply or removal of fluid, for instance a lubricator or a filling aperture 21, in order that the regulating device may be adjusted for a certain 95 pressure or a certain temperature in the boiler.

Claims:

1. In a regulating device for electrode boilers, the combination with the boiler having interior electrodes and means for adjusting the resistance between the electrodes, of a container filled with and enclosing a transferring liquid separated by fixed walls from the boiler contents, said container being in part arranged inside the boiler subject to varying temperature therein, means being arranged between the said liquid and the said adjusting means in such a manner that variations in heat extensions and retraction of the liquid are transferred to the said adjusting means for regulating the electric resistance.

2. In a regulating device for electrode boilers, the combination with the boiler having interior electrodes and means for adjusting the resistance between the electrodes, of a container filled with and enclosing a transferring liquid separated by fixed walls from the boiler contents, said container being in part arranged inside the boiler subject to varying temperature and pressure therein, means being arranged between the said liquid and the said adjusting means in such a manner that variations in the liquid on account of varying temperature and pressure in the boiler are transferred to the said adjusting means for regulating the electric resistance.

3. In a regulating device for electrode boilers, the combination with the boiler having interior electrodes and means for adjusting the resistance between the electrodes, of a 5 container filled with and enclosing a transferring liquid separated by fixed walls from the boiler contents, said container being in part arranged inside the boiler subject to varying temperature therein, a piston cylinder 10 forming part of the container, a piston movable in the cylinder subject to varying pressure from the liquid, means arranged between the piston and the said adjusting means in such a manner that variations in 15 heat extension or retraction of the liquid are transferred to the said adjusting means for regulating the electric resistance.
4. In a regulating device for electrode boilers, the combination with the boiler having 20 interior electrodes and means for adjusting the resistance between the electrodes, of a container filled with and enclosing a transferring liquid separated by fixed walls from the boiler contents, said container being in 25 part arranged inside the boiler subject to varying temperature and pressure therein, a piston cylinder forming part of the container, a piston movable in the cylinder subject to varying pressure from the liquid, means arranged between the piston and the said adjusting means in such a manner that variations in the liquid on account of varying temperature and pressure in the boiler 30 are transferred to the said adjusting means for regulating the electric resistance.
5. In a regulating device for electrode boilers, the combination with the boiler having interior electrodes and means for adjusting the resistance between the electrodes, of a 35 container filled with and enclosing a transferring liquid separated by fixed walls from the boiler contents, said container being in part arranged inside the boiler subject to varying temperature and pressure therein, flexible walls forming part of the walls of the container portion arranged inside the boiler, said flexible walls causing the liquid in the container to be moved out from or drawn into the same, and means actuated by 40 such movement of the liquid so as to regulate the electric resistance in accordance with the varying pressure in the boiler.
6. In a regulating device for electrode boilers, the combination with the boiler having 45 interior electrodes and means for adjusting the resistance between the electrodes, of an actuating member, means for causing movement of said member in accordance with varying temperature in the boiler, a link (a) 50 connected with the said actuating member, other links (b, c) having a common connection (9) with the first link (a), one (b) of the other links having a fixed fulcrum (10), whereas the remaining one (c) has a connection (at 11) with the said 55 connection (at 11) with the said means for adjusting the resistance.
7. In a regulating device for electrode boilers, the combination with the boilers having interior electrodes and means for adjusting the resistance between the electrodes, of an 60 actuating member, means for causing movement of said member in accordance with varying temperature and pressure in the boiler, a link (a) connected with the said actuating member, other links (b, c) having a common connection (9) with the first link (a), one (b) of the other links having a fixed fulcrum (10), whereas the remaining one (c) has a connection (at 11) with the said 65 means for adjusting the resistance.
8. In a regulating device for electrode boilers, the combination with the boiler having interior electrodes and means for adjusting the resistance between the electrodes, of an 70 actuating member, means for causing movement of said member in accordance with varying temperature in the boiler, a link (9) connected (at 12) with the said actuating member, other links (b, c, c₂ . . .) having a common connection (8) with the first link (a), one (b) of the other links having a fixed fulcrum (10), whereas the remaining ones (c, c₂ . . .) have a connection (11, 11² . . . respectively) with members adapted to adjust the resistance between 75 the electrodes.
9. In a regulating device for electrode boilers, the combination with the boiler having interior electrodes and means for adjusting the resistance between the electrodes, of an 80 actuating member, means for causing movement of said member in accordance with varying temperature and pressure in the boiler, a link (9) connected (at 12) with the said actuating member, other links (b, c, c₂ . . .) having a common connection (8) with the first link (a), one (b) of the other links having a fixed fulcrum (10), whereas each of the remaining ones (c, c₂ . . .) have a connection (11, 11² . . . respectively) with members adapted to adjust the resistance between 85 the electrodes.
10. In a regulating device for electrode boilers, the combination with the boiler having interior electrodes and means for adjusting the resistance between the electrodes, of an 90 actuating member, means for causing movement of said member in accordance with varying temperature and pressure in the boiler, a link (9) connected (at 12) with the said actuating member, other links (b, c, c₂ . . .) having a common connection (9) with the first link (a), one (b) of the other links having a fixed fulcrum (10), whereas each of the remaining ones (c, c₂ . . .) have a connection (11, 11² . . . respectively) with members adapted to adjust the resistance between 95 the electrodes.
11. In a regulating device for electrode boilers, the combination with the boiler having interior electrodes and means for adjusting the resistance between the electrodes, of an 100 actuating member, means for causing movement of said member in accordance with varying temperature and pressure in the boiler, a link (9) connected (at 12) with the said actuating member, other links (b, c, c₂ . . .) having a common connection (9) with the first link (a), one (b) of the other links having a fixed fulcrum (10), whereas each of the remaining ones (c, c₂ . . .) have a connection (11, 11² . . . respectively) with members adapted to adjust the resistance between 105 the electrodes.
12. In a regulating device for electrode boilers, the combination with the boiler having interior electrodes and means for adjusting the resistance between the electrodes, of an 110 actuating member, means for causing movement of said member in accordance with varying temperature and pressure in the boiler, a link (9) connected (at 12) with the said actuating member, other links (b, c, c₂ . . .) having a common connection (9) with the first link (a), one (b) of the other links having a fixed fulcrum (10), whereas each of the remaining ones (c, c₂ . . .) have a connection (11, 11² . . . respectively) with members adapted to adjust the resistance between 115 the electrodes.
13. In a regulating device for electrode boilers, the combination with the boiler having interior electrodes and means for adjusting the resistance between the electrodes, of an 120 actuating member, means for causing movement of said member in accordance with varying temperature in the boiler, a link (9) connected (at 12) with the said actuating member, other links (b, c, c₂ . . .) having a common connection (9) with the first link (a), one (b) of the other links having a fixed fulcrum (10), whereas each of the remaining ones (c, c₂) have a connection (11, 11²) respectively with a member (7, 7²) each adapted to adjust a portion of the resistance 125 between the electrodes.

11. In a regulating device for electrode boilers, the combination with the boiler having interior electrodes and means for adjusting the resistance between the electrodes, of an actuating member, means for causing movement of said member in accordance with varying temperature and pressure in the boiler, a link (a) connected (at 12) with the said actuating member, other links (b, c, $c_2 \dots$) having a common connection (9) with the first link (a), one (b) of the other links having a fixed fulcrum (10), whereas each of the remaining ones ($c, c_2 \dots$) have a connection (11, 11² $\dots$ respectively) with members 70

accordance with varying temperature in the boiler, a link (9) connected (at 12) with the said actuating member, other links (b, c, c₂, ...) having a common connection (9) with the first link (a), one (b) of the other links having a fixed fulcrum (10), whereas each of the remaining ones (c, c₂, ...) have a connection (11, 11², ...) respectively with a member (7, 7², ...) each adapted to adjust a portion of the resistance between the electrodes.

18. In a regulating device for electrode boilers, the combination with the boiler having interior electrodes and means for adjusting the resistance between the electrodes, of a container filled with and enclosing a transferring liquid separated by fixed walls from the boiler contents, said container being in part arranged inside the boiler subject to varying temperature therein, means supplying liquid to or removing liquid from the said completely filled container, means being arranged between the said liquid and the said adjusting means in such a manner that variations in heat extension and retraction of the liquid are transferred to the said adjusting means for regulating the electric resistance.

19. In a regulating device for electrode boilers, the combination with the boiler having interior electrodes and means for adjusting the resistance between the electrodes, of a container filled with and enclosing a transferring liquid separated by fixed walls from the boiler contents, said container being in part arranged inside the boiler subject to varying temperature therein a filling aperture (21) provided on the container and enabling liquid to be supplied to or removed from the said completely filled container, means being arranged between the said liquid and the said adjusting means in such a manner that variations in heat extension and retraction of the liquid are transferred to the said adjusting means for regulating the electric resistance.

20. In a regulating device for electrode boilers, the combination with the boiler having interior electrodes and means for adjusting the resistance between the electrodes, of a container filled with and enclosing a transferring liquid separated by fixed walls from the boiler contents, said container being in part arranged inside the boiler subject to vary temperature therein, a lubricator communicating with a filling aperture (21) provided on the container and enabling liquid to be supplied to or removed from the said completely filled container, means being arranged between the said liquid and the said adjusting means in such a manner that variations in heat extension and retractions of the liquid

are transferred to the said adjusting means for regulating the electric resistance.

21. In a regulating device for electrode boilers, the combination with the boiler having interior electrodes and means for adjusting the resistance between the electrodes, of a container filled with and enclosing a transferring liquid separated by fixed walls from the boiler contents, said container being in part arranged inside the boiler subject to varying temperature and pressure therein, means supplying liquid to or removing liquid from the said completely filled container, means being arranged between the said liquid and the said adjusting means in such a manner that variations in the liquid on account of varying temperature and pressure in the boiler are transferred to the said adjusting means for regulating the electric resistance.

22. In a regulating device for electrode boilers, the combination with the boiler having interior electrodes and means for adjusting the resistance between the electrodes, of a container filled with and enclosing a transferring liquid separated by fixed walls from the boiler contents, said container being in part arranged inside the boiler subject to varying temperature and pressure therein, a filling aperture (21) provided on the container and enabling liquid to be supplied to or removed from the said completely filled container, means being arranged between the said liquid and the said adjusting means in such a manner that variations in the liquid on account of varying temperature and pressure in the boiler are transferred to the said adjusting means for regulating the electric resistance.

23. In a regulating device for electrode boilers, the combination with the boiler having interior electrodes and means for adjusting the resistance between the electrodes, of a container filled with and enclosing a transferring liquid separated by fixed walls from the boiler contents, said container being in part arranged inside the boiler subject to varying temperature and pressure therein, a lubricator communicating with a filling aperture (21) provided on the container and enabling liquid to be supplied to or removed from the said completely filled container, means being arranged between the said liquid and the said adjusting means in such a manner that variations in heat extension and retraction of the liquid are transferred to the said adjusting means for regulating the electric resistance.

In testimony whereof I have signed my name to this specification.

SÖREN DAVIDSEN.
